CIRCUIT INTERRUPTER

Benjamin P. Baker, Turtle Creek, and Winthrop M. Leeds, Wilkinsburg, Pa., assignors to Westinghouse Electric & Manufacturing Company, East Pittsburgh, Pa., a corporation of Pennsylvania

Application January 24, 1940, Serial No. 315,372

8 Claims. (Cl. 200—150)

This invention relates to improvements in circuit interrupters, and more particularly to circuit breakers of the liquid immersed type. In United States Patent No. 1,942,294, issued January 2, 1934, to W. Kaufmann, is shown and described a circuit interrupter which operates on the expansion principle. Circuit interruption in accordance with this principle is accomplished by surrounding the arc with a vaporized fluid under pressure and suddenly decreasing the pressure of the fluid to effect a change of state from the super-heated to the saturated condition, which condition is caused to persist at least during the time the arc current passes through one current zero. The suddenly cooled vapor condenses on the electric charge carriers in the arc path to increase their mass to such a degree that their velocity is decreased to a value below that which is necessary to re-ionize the arc path under the influence of the rising voltage following a current zero. Further, in accordance with the patent, the sudden expansion of the vapor in the arc chamber is obtained by pressure responsive opening a plurality of vents close to and along the length of the arc. We have discovered that the interrupting ability of a circuit breaker of the type disclosed in the aforesaid patent is quite sensitive to changes in the diameter of the arc chamber openings through which the moving contact operates, and that the interrupting capacity of a breaker of this type is limited to approximately 800,000 kva. at 15,000 volts.

The main object of our invention is to improve the interrupting ability of circuit breakers of the liquid immersed type in which arc extinction is dependent upon subjecting the arc to a turbulent blast of gas or mixture of gas and liquid.

Our invention contemplates the provision of a liquid immersed breaker having an arc chamber generally of the form disclosed by the aforesaid Kaufmann patent but which necessarily does not depend upon the expansion theory of operation to bring about arc extinction but which relies principally upon obtaining de-ionization of the arc stream by subjecting it to a turbulent blast of arc-extinguishing gas or mixture of gas and liquid.

The more specific object of our invention is to improve the interrupting ability of circuit breakers of the aforesaid type by the provision of venting means for the pressure chamber at or near one end thereof, so as to subject greater portions of the arc length to a more turbulent blast of arc extinguishing gas, and further to provide venting means, the opening of which is responsive to the

pressure in the arc chamber for controlling the degree of venting in accordance with the current to be interrupted.

A further object of the invention resides in improving the interrupting ability of liquid immersed breakers by the provision of means for injecting additional liquid into the arc stream in response to opening of the vent in the pressure chamber.

10 Another object of the invention is to provide an arc chamber for liquid immersed circuit interrupters wherein the interrupting effectiveness is maintained to the end of the opening stroke of the moving contact member.

15 It is also an object of our invention to improve the general performance of a circuit breaker of the type above referred to by the provision of means for absorbing the sudden release of energy occasioned by venting the pressure chamber, so as to relieve the breaker casing of disruptive stresses.

20 Other objects and advantages will be apparent from the following description when taken in connection with the accompanying drawings, in which:

25 Figure 1 is a sectional view illustrating the circuit breaker of our invention, taken along the line I—I of Fig. 2;

Fig. 2 is a cross-sectional view taken along the line II—II of Fig. 1; and

Fig. 3 is a fragmentary sectional view showing a modified form of breaker construction.

30 In the drawings, the reference numeral 5 designates a tubular casing member of insulating material having a metallic flange 7 secured to the lower end thereof. The flange member 7 has a plurality of outwardly extending lugs 9, from which is suspended, as by bolts 11, a metallic casing member 13. Disposed between the tubular casing 5 and the casing member 13 is an annular support blade 15. Suitable gaskets, as shown, are provided between the meeting surfaces of the casings 5 and 13 with the plate 15, so that when the bolts 11 are drawn up, a liquid-tight joint will be obtained. Bolted to the lower side of the annular plate 15 is a flanged cup-like member 17 which depends into the lower casing member 13. The cup-shaped member 17 is preferably made of conducting material, and is utilized to support a stationary contact assembly

40 45 50 55 comprising a hollow cylindrical member 21 in which are disposed a plurality of yieldingly mounted finger contacts 23. Disposed within the annular plate 15 and resting upon the upper flange of the support 17 is a ring member 25 of

insulating material, which carries a plurality of blocks 27 of insulating material of generally rectangular form, as more clearly shown in Fig. 2.

The blocks 27 have rounded corners and diagonal dimensions substantially equal to the inner diameter of the casing member 5. The side edges of the blocks 27 are also preferably rounded so as to insure freedom of movement of the blocks in an axial direction of the cylindrical casing 5 for a purpose which will be more fully explained hereinafter. Each of the blocks 27 is provided with a central aperture 29 and an annularly disposed pocket 31 extending radially from the aperture 29. Thus the apertures 29 and the pockets 31 form a restricted arc passage rising above the stationary contact assembly 19. Resting upon the uppermost block member 27 is a tubular piston member 33 also of insulating material having a passage therethrough of a diameter considerably greater than the apertures 29 in the blocks 27.

The upper end of the piston member 33 is guided by a cylindrical guide member 35, which in turn is supported by a plurality of bolts 37 carried by inwardly extending lugs 39 of a 25 metallic cylindrical lining member 41. Disposed between the guide member 35 and the upper end of the piston 33 is a ring 43 of resilient compressible material, such as rubber, which maintains the piston member 33 and the blocks 27 in compression, as well as maintaining the entire assembly firmly seated upon the insulating ring 25. The transverse wall portion of the guide member 35 is provided with a bushing 45 through which a movable contact rod 47 is adapted to 30 operate.

The contact rod 47 is preferably of a diameter slightly less than the apertures 29 through which it is adapted to move in making and breaking contacting engagement with the contact fingers 25. Thus the guide member 35, the piston member 33, blocks 27, the insulating ring 25 and the support member 17 provide a substantially 40 closed pressure chamber in which an arc may be drawn upon the withdrawal of the contact rod 47 from the stationary contact assembly 19.

The upper end of the metallic tubular member 41 has an outwardly extending flange 49, to which is secured a support plate 51. The plate 51 has a recessed portion 53 carrying a guide member 55 through which the contact rod 47 is adapted to be moved. Also secured to the plate 51 is a hollow casing 57 which houses the moving contact operating mechanism generally indicated at 59, whereby the contact rod 47 is operated to open and closed circuit positions.

An electrical connection is made from the upper end of the contact rod 47 by a flexible conductor 61 to a terminal 63 which serves as one of the line terminals for the interrupter. The other line connection may be made to a terminal connector 65 secured to the annular plate 15. Thus an electrical circuit is established through the interrupter by way of line terminal 63, flexible conductor 61, movable contact 47, stationary contact assembly 19, support member 17, annular plate 15 to the other line terminal 65.

The casing 5 is preferably filled with arc extinguishing liquid to a level so as to completely immerse the pressure chamber and maintain the same completely filled with liquid. In order to insure that the pressure chamber, as defined by the piston member 33 and the blocks 27, is maintained filled with liquid, the insulating 70

ring member 25 may be provided with a plurality of vent passages 67.

The operation of the interrupter is as follows: In the event it is desired to open the circuit 5 interrupter under conditions of load, the operating linkage 59 is actuated by a suitable operating mechanism (not shown) to raise the moving contact rod 47 to disengage the contact rod from the contact fingers 23, and thereby establish an 10 arc in the apertures 29 and the liquid retaining pockets 31. As soon as arcing takes place, pressure builds up within the pressure chamber and reacts upon the lower pressure exposed area of the lowermost block 27. Inasmuch as this area 15 is greater than the upper area of the tubular piston member 33, the net result is to move the block assembly 27 and the piston 33 upwardly. Thus the pressure chamber will vent between the lower block 27 and the insulating ring 25. During the interruption of very low currents the pressure within the arc chamber may not be sufficient to raise the blocks 27 from the ring 20 25 in which case venting of the arc chamber takes place through the permanent passages 67.

The gases formed by the action of the arc on a liquid turbulent intermix with the arc stream and pass longitudinally thereof through the vent opening, as above described, and hence pass upwardly around the outer sides of the blocks 27 through the arc extinguishing liquid to the space above the liquid in the upper end of the casing 5. In the event that water is used as the arc extinguishing liquid, it will, of course, be understood that a greater percentage of vapor 30 produced is in the form of steam, and will condense in passing through the body of liquid contained outside of the pressure chamber. The gases rising from the liquid, including the permanent gases, which are formed as a result of the action of the arc, are permitted to escape through an opening 69 disposed in the plate 51 into an exhaust stack 71 provided on the side of the casing 51. Baffle plates 72 are provided in the stack 71 for separating the liquid and gases discharged into the stack and also serve to condense the escaping water vapor.

It should also be understood that insulating liquids may be used in the interrupter forming greater quantities of non-condensable gases, 45 which will also rise to the surface of the liquid and escape through the exhaust stack 71, as before mentioned.

It will also be noted that as the blocks 27 are raised, the piston member 33 is forced against the rubber ring 43 and displaces liquid from within the guide member 35 axially of the moving contact 47 into the arc stream. It has been found that this liquid displacing action has been materially effective in increasing the interrupting capacity of the breaker, in that relatively cool liquid is mixed with the vapor so that at the first or second current zero the dielectric strength builds up more rapidly, thereby making re-ignition of the arc impossible.

During the circuit interrupting operation arcing is more severe in the region just above the stationary contact assembly 19 and decreases in intensity with an increase in arc resistance as the arc is lengthened. The insulating material defining the arc passage or pressure chamber is, therefore, subject to greater erosive effects at or near the stationary contact assembly 19 than at points more remote from the assembly. The repeated action of an arc upon the inner walls of the pressure chamber make it necessary to

replace the pressure chamber at given intervals in order to maintain the interrupting efficiency of the breaker at a high value. Inasmuch as the erosion of the pressure chamber takes place principally at or near the stationary contact assembly 19, this particular portion of the pressure chamber is formed of a plurality of sections or blocks 27. Therefore, in the event that the aperture 29 in the lowermost block 27 becomes enlarged to a degree influencing the efficiency of the interrupter, it merely is necessary to replace one block of insulation instead of the entire pressure chamber. The multi-section arrangement has the further advantage over a solid construction in that the radially extending annular pockets 31 can be more easily provided in the former arrangement than in the latter.

It should be noted that the contiguous surfaces of the blocks 27 are confined to a relatively small annular area about the apertures 29. This is accomplished by recessing the middle and lowermost blocks 27, as shown at 73 in Fig. 1. Thus, if there is any tendency for the blocks 27 to separate by pressure acting between the contacting surfaces, this pressure is so quickly dissipated through the recesses 73 that it cannot be maintained, and causes the blocks 27 to remain in contacting engagement and move as a unit to vent the pressure chamber only at the lower end at the gap formed between the lower block 27 and the insulating ring 25. By thus keeping the blocks 27 and the piston 33 in contacting engagement, the entire movement of gas formed by the action of the arc as it is drawn upwardly through the blocks is longitudinally of the arc in a direction opposite to that of arc movement which also assists in arc extinction.

Inasmuch as interrupters of the type herein described develop sudden changes in pressure within the interrupting chamber and surrounding casing, suitable means are required for absorbing the energy when the pressure within the pressure chamber is released. Absorption of the energy upon opening of the vent from the pressure chamber may be accomplished by the use of a plurality of elastic bodies 75 disposed about the support member 17 in the lower casing member 13. The elastic bodies 75, for example, may constitute rubber hose filled with air. A further form of energy absorbing means is shown in Fig. 3 which is similar in all respects to Fig. 1, with the exception that the support member 17 is provided with a downwardly extending annular member 77 disposed in surrounding spaced relation so as to form an annular gas pocket 79. When the pressure chamber in the arrangement shown in Fig. 3 is vented by the upward movement of the blocks 27, the energy thus imparted to the liquid in the casing 13 will be absorbed by the elastic body of gas trapped in the annular space 79 and thereby relieve the casing of the interrupter of disruptive stresses.

From the foregoing description, it is to be understood that the various parts of the interrupter are constructed of materials most suitable to resist action of the arc and corrosion of the particular liquid used to extinguish the arc. For example, in the event that water is used as an arc extinguishing liquid, the metallic parts are preferably made of brass or bronze which will resist the corrosion of water. The insulating parts, such as the casing 5, the blocks 27 and the piston member 33, are preferably constructed of resinous material of either molded or compressed form such as will withstand the action

of water. It is also desirable in this instance to use a resilient ring 43 of rubber. However, in the event of the use of oil as an arc extinguishing liquid, many of the metallic parts, such as the guide member 35 and the casing 13, may be constructed of steel, and the resilient member 43 may be replaced by a steel spring. The insulating member 33 and the blocks 27 in the latter instance would preferably be made of fibre or similar arc-resisting material.

Although we have shown and described a specific circuit-interrupting structure and have enumerated several materials, the use for which we have a preference, it is to be understood that the same is for the purpose of illustration, and that changes and modifications may be made by those skilled in the art without departing from the spirit and scope of the appended claims.

We claim as our invention:

- 20 1. In a circuit interrupter, relatively movable contact members for opening and closing the circuit, an arc extinguishing device surrounding said contact members comprising means of insulating material defining a side wall member and end members to provide a substantially closed pressure chamber, arc extinguishing liquid in said chamber, means supporting said wall member for relative movement with respect to said end members in response to arcing pressure within said chamber, said wall member separating from one of said end members during said movement to provide a vent opening for said chamber, and means coacting with the other end member and said wall member operative in response to movement of the latter for moving a quantity of arc extinguishing liquid through said pressure chamber towards said vent opening.
- 25 2. In a circuit interrupter, relatively movable contact members for opening and closing the circuit, an arc extinguishing device surrounding said contact members comprising means of insulating material defining a side wall member and end members to provide a substantially closed pressure chamber, arc extinguishing liquid in said chamber, said side wall member being disposed in movable relation with respect to said end members and movable in response to pressure within said chamber away from one of said end members to establish a vent between said side wall member and said one end member, resilient means for biasing said side wall member into engagement with said one end member to normally close said vent, and means responsive to movement of said wall member toward the other of said end members for moving a quantity of said arc extinguishing liquid toward said vent.
- 30 3. In a circuit interrupter, a casing including a plurality of sections defining an elongated arc passage having a constricted portion and a portion of greater cross-sectional area and end members closing said passage to provide a pressure chamber, arc extinguishing liquid in said casing, resilient means biasing said sections together and towards one of said end members, and separable contacts within said casing for establishing an arc along said arc passage, said sections being movable as a unit in response to predetermined pressure conditions within said chamber to establish a vent between said one end member and the constricted arc passage end of said casing, and means responsive to said movement of said sections to cause liquid to be displaced from the larger portion of said arc passage to the constricted portion of said passage.
- 35 4. In a circuit interrupter, an arc extinguish-

ing device comprising a body member having a passage therethrough and end members closing said passage to define a pressure chamber, arc extinguishing liquid in said chamber, and contact members separable in said chamber to establish an arc, said body member being disposed for relative movement with respect to said end members and having differential pressure reactive areas arranged to cause movement of said body member away from one of said end members in response to arc pressure within said chamber to provide a vent opening between said one end member and said body member, and means responsive to movement of said body member for displacing a quantity of liquid longitudinally of said passage to assist extinction of the arc.

5. In a circuit interrupter, a support member, a stationary contact mounted thereon, a coacting movable contact, a body member having a passage therethrough, means biasing said body member into engagement with said support member to close one end of said passage, said movable contact being operable in said passage to establish an arc therealong, and an end member having a cavity therein leading to said passage and closing the other end thereof, and being arranged for relative movement with respect to said body member, arc extinguishing liquid filling said passage, said body member being movable away from said support member in response to predetermined pressure conditions in said passage to establish a vent only at said stationary contact and into the cavity of said end member to force a quantity of arc extinguishing liquid longitudinally of said passage in the direction of said stationary contact.

6. In a circuit interrupter, a stationary contact, a coacting movable contact, an arc extinguishing device including a substantially closed pressure chamber surrounding said contacts, arc extinguishing liquid in said chamber, said pressure chamber including a plurality of wall sections, a plurality of said sections having their inner walls recessed to provide liquid retaining pockets, and means biasing said sections together and towards said stationary contact, said sections being movable as a unit against the biasing action of said biasing means in response to pressure in said chamber to establish a vent only at said station- 50

ary contact for decreasing the pressure and for causing a blast of liquid longitudinally of the arc.

7. In a circuit interrupter, wall means of insulating material defining an elongated arc passage, a stationary support normally closing one end of said passage, a hollow casing enclosing the other end of said passage, said wall means having limited longitudinal movement between 10 said support and casing, a quantity of arc extinguishing liquid in said arc passage, means for establishing an arc in said arc passage, and resilient means disposed in said hollow casing for normally biasing said wall means toward said support, said wall means having inner surface areas so arranged to cause the pressure produced by the arc to move said wall means against the action of said resilient means to open a vent between said support and said wall means, and move said wall means into said hollow casing to force a quantity of said arc extinguishing liquid from said casing through said arc passage.

8. In a circuit interrupter, a hollow support, a stationary contact within said support, a plurality of sections of insulating material disposed in contiguous relation upon said support, said sections having an opening therethrough to provide an arc passage, said support normally closing one end of said passage, a movable contact 25 coacting with said stationary contact and actuatable through said sections to establish an arc in said passage, arc extinguishing liquid in said passage, a hollow casing member disposed in telescopic relation with the end one of said sections 30 and adapted to close the other end of said passage, and a resilient member disposed in said hollow casing for biasing said sections as a unit toward said support, said arc passage within said sections having pressure reactive surfaces so arranged to cause movement of said sections as a unit against said resilient member in response to pressure within said passage for opening a vent between said support member and the adjacent insulating section, and further to cause one end 35 section to displace arc extinguishing liquid from said hollow casing member and establish a flow of said liquid through said arc passage.
